(57) **CLAIM**

I claim the ornamental design for a surveillance camera mount, as shown and described.

DESCRIPTION

FIG. 1 is a front perspective view of a surveillance camera mount of the present invention;

FIG. 2 is a rear perspective view thereof;

FIG. 3 is a front view thereof;

FIG. 4 is a rear view thereof;

FIG. 5 is a left side view thereof;

FIG. 6 is a top view thereof;

FIG. 7 is a bottom view thereof; and,

FIG. 8 is a right side view thereof.

The broken lines depict portions of the surveillance camera mount that form no part of the claimed design.
